FLUID CONTROL VALVE

William A. Ray, Los Angeles, Calif.

Application October 4, 1941, Serial No. 413,619

5 Claims. (Cl. 137—144)

My present invention relates to fluid control valves and particularly to those of the type adapted to control fluid flow through both a main and a supplemental outlet. The invention, while not so limited, has particular utility in connection with a "safety" valve of the type wherein a main closure member is maintained in open position by means responsive to a controlling condition—such as that due to the existence of flame at a pilot burner for a main burner whose fuel supply is controlled by the valve—and is released upon extinction of the pilot burner flame, so that it then closes and must subsequently be "manually reset" to its open position. When the safety valve closes, it is desirable that the supply of fuel to the extinguished pilot burner also be automatically shut off until the valve is reset. It is therefore a general object of my invention to provide supplemental valve means for so controlling the pilot burner.

A combination valve of the character described is disclosed in my copending application, Serial No. 377,274, filed February 4, 1941, and it is an object of the present invention to improve that valve in certain respects.

Another object is the provision of a combination valve of the character described wherein the supplemental valve comprises a unit which is independent of the means for operating the main or safety valve, to the extent that it is only indirectly operated and is maintained in its open position by the safety valve when the same is open.

Another object is the provision of a supplemental valve which is so constructed and arranged that it is substantially leakproof.

Another object is the provision of a combination valve of the character described which is particularly adapted to the control of a unit of a multiple-unit burner system.

Other objects and advantages of this invention will be found in the description, the drawings, and the appended claims.

For complete understanding of the invention, reference may be had to the following detailed description and accompanying drawings, wherein:

Figure 1 is a view, mainly in vertical section, of a combination valve embodying my invention;

Figure 2 is a plan of the same valve with the cap 35 cut away along the line 2—2 of Fig. 1;

Figure 3 is a vertical section taken along the irregular line 3—3 of Fig. 1;

Figure 4 is a fragmentary detail section taken along the line 4—4 of Fig. 1; and

Figure 5 is a diagrammatic view of a multiple-unit burner control system, illustrating a preferred application of the valve shown in the other figures.

In the drawings, the numeral 11 indicates an upper, or main, valve casing, to the open bottom end of which is secured a sub-casing 12. The main casing 11 has an inlet connection 13 and an outlet connection 14 and is internally bored in its upper portion to provide a tapered seat 15 for a correspondingly tapered plug 16. In the bottom portion of this plug is a concentric opening or passage 17, from the upper end of which branches a lateral passage 18 which, in the rotation of the plug, is adapted to register with a lateral passage 19 in the casing which connects with the outlet connection 14. The portion of the casing 11 surrounding the cylindrical bottom end of the plug seat 15 forms a knife-edged annular valve seat 20, cooperable with which is a closure member generally indicated at 21. The cylindrical lower portion or stem 22 of this member is slidable in a bushing 23 which is secured in a central opening in a disk 24. The marginal portion of this disk is received in a shallow recess formed in the bottom of the casing 11 and is held therein by means contained in the sub-casing 12 and which will hereinafter be described. The closure member 21 is guided at its upper end by a plurality of spaced portions 25 extending from the inner wall of the casing 11.

For the operation of the closure member 21, a channelled arm 26 is provided which is pivoted at one of its ends on a bracket 27 secured to an upper surface of the sub-casing 12, the bifurcated other end of the arm abutting the opposite flat sides of a hexagonal upper portion of the stem 22 and having elongated openings for receiving the projecting ends of a pin 28 secured in that portion. For actuating the arm 26, a rod 29 is provided which is reciprocable in a bore 30 formed in an upper portion of the main casing. This bore is enlarged toward its upper end to accommodate a spring 31 surrounding the rod and urging the same upward so that normally the conical upper surface of the enlarged lower end 32 of the rod is in engagement with the casing adjacent the bottom end of the bore 30, thereby preventing any possible leakage of fluid around the rod when it is in that position. In the drawings, the rod 29 is shown in its manually depressed position (wherein leakage around the rod

is prevented by packing means 33 provided below the spring 31) with its lower portion 32 in engagement with the arm 26, the same being in a moved position such that the closure member 21 is held away from its seat 20. Biasing the closure member toward its seat is a torsion spring 34 connected to the arm 26 and bracket 27.

Rotatably mounted on an extreme upper portion of the casing 11 is a manually-operable hollow cap 35, the undersurface of which is annularly recessed at 36 to normally provide a clearance space for a ball 37 which rests on the top end of rod 29 in the upper end of the enlargement of bore 30. The cap is mounted for free rotation by means of a plurality of balls 38 which are arranged in cooperating semi-spherical annular grooves formed in the inner side wall of the cap and in the adjacent cylindrical portion of the casing. A plug 39 closes an opening in the cap whereby the balls can be introduced. As is better seen in Fig. 3, a wedge-shaped member or cam 40 is secured in the recess 36 in a position such that, in the manual rotation of the cap in a clockwise direction as viewed from above, its inclined front end engages the ball 37 and forces it downward, thereby operating the closure member 21 through the agency of rod 29 and arm 26—the parts being shown in such positions in the drawings.

The cylindrical upper portion 41 of the plug 16 is reduced in diameter at its upper extremity, this reduced portion being milled to provide opposite flat sides and threaded for a nut 42. Held to the plug by this nut is a segment plate 43 having a broached central opening corresponding to the flat-sided portion of the plug; and below the plate, in a recess of the casing around the plug portion 41, is a compression spring 44 which urges the plug upward into firm engagement with its tapered seat 15. The upper portion of the cap 35 has a pair of recesses 45 (Fig. 2) for receiving tongue portions 46 of the plate 43, whereby the plug can be rotated by means of the cap. These tongues and recesses are so proportioned that there is about 15° lost-motion between the cap and the plug-driving plate 43, so that when the cap is released it is rotated in a counterclockwise direction by the upward movement of rod 29 (under the influence of spring 31) acting on cam 40, there being no material resistance to such rotation of the cap since it is not now connected to the plug on account of the lost-motion permitted between these parts. If such lost-motion were not provided, there would be the possibility that, on account of the relatively great friction between the tapered plug and its seat, the closure member 21 would be held in open position upon release of the cap—regardless of the condition of "safety" means (hereinafter to be described) for so holding it. Rotation of the plate 43, and hence that of the plug 16, is limited to an angle of about 110° by a pair of stops 47 which extend from the top surface of the casing 11 and are engageable by the segment shoulders 48 and 49. When the plug is rotated, by means of cap 35, in a counterclockwise direction through this 110° from its closed position as shown in the drawing, the plate shoulders 49 are in engagement with the stops 48 and the plug passage 18 is in register with the casing passage 19. The reason for the plug, in its closed position, being at an angle greater than 90° with respect to its full-open position, is so that there is then a considerable distance between the mouths of the

passages 18 and 19 which ensures against possible leakage in spite of wear adjacent these mouths.

Carried on the bottom end of the closure member stem 22 is an armature 55 which is cooperable with an electromagnet, generally indicated at 56, mounted in the sub-casing 12 and comprising a U-shaped core 57 which carries on one of its arms an energizing coil 58. The leads of this coil are soldered to a pair of hexagonal terminal posts 59, insulatingly secured to the bottom wall of the sub-casing by hexagon-headed hollow screws 60 (Fig. 4) in which are threaded screws 61 for the connection of external wiring. To prevent possible rotation of the posts 59 (and consequent damage to the coil leads) when external electrical connections are made or removed, a disk 62 of insulating material is provided, the disk fitting snugly within the sub-housing and having a pair of hexagonal openings for the posts. The disk rests on the upper insulating washers 63 of the terminal posts and on a raised portion 64 of the sub-casing, and also serves to hold in position the core 57, the arms of which extend upward through a generally-rectangular central opening in the disk. A U-shaped metal strap 65 embraces the medial portion of the core and is outwardly bent-over at its ends below the disk 62 to hold the bottom of the core in a recess 66 provided for it in the bottom wall of the sub-casing.

The disk 62 is held from vertical movement by a pair of opposed cup-shaped shells 67 and 68 which fit snugly within the sub-housing 12, and the interengaging end walls of which are apertured to receive the upper end portions of the core arms. The combined length of the shells is such that, when in position, the mouth of the upper shell 68 is flush with the upper surface of the sub-housing so that the shells serve not only to hold the disk 62 and the electromagnet in position, but also the plate 24 in its recess in the upper casing 11 (through a gasket 69 which seals the junction between the upper casing and the sub-casing).

The armature 55 is loosely mounted on a rod 70 secured to the closure member stem 22, and is of rectangular shape and only slightly larger than the pole faces formed at the extremities of the arms of core 57 and the space between them. Since the nickel-iron alloy, of which the armature is preferably constructed, is expensive and not readily obtainable at this time, there is a worthwhile saving of material in providing such an armature in place of one of conventional circular shape. To limit rotation of the armature on rod 70 to a small angle, the armature is transversely slotted at 71 to freely receive the straight-sided portion of the otherwise cylindrical head 72 of the rod 70. The portion between the rod and its head is rounded to permit the armature to rock slightly in all directions so that it can conform exactly to the pole faces of the core when it is magnetically held thereto and there is an upward force on the rod 70. This is important, since the electromagnet 56 is designed to operate on power only sufficient to magnetically hold the armature, against an opposing force, after it is first manually brought into engagement with its pole faces, and any slight misalignment of these parts would greatly weaken the holding force. The armature is normally (when stem 22 is in its raised position) held against the head 72 by the force of a light spring 73 compressed between it and the bottom end of stem 22. This spring permits a small amount of longitudinal relative

movement of the armature and rod 70, so that the armature can be brought into firm engagement with the pole faces (as shown in Fig. 1) without the possibility of damage or distortion of the parts by excessive downward force on the stem 22.

In a thickened portion of the side wall of the sub-housing 12 is a vertical bore 11, the bottom end of which is closed by a screw plug 18. Within the bore 11 is a supplemental-valve ball 79, having a diameter considerably less than that of the bore, which is upwardly urged by a compression spring 80, the lower end of which is received in a recess in the plug 18. The bore 11 is reduced in diameter toward its upper end to provide a seat 81 for the ball, and is still further reduced at its uppermost end to form a close guide for a rod 82, the bottom and top ends of which are respectively in engagement with the ball 79 and the underside of the cross portion of the channelled arm 26. To provide a relatively long leak-proof guide for the rod 82, a boss 83 is formed on the upper portion of the sub-casing around this rod. Branching laterally from opposite sides of the lower end of bore 11 are passages 84 and 85 which extend to the exterior of the sub-casing, their outer ends being enlarged to receive pipe fittings 86 and 87. It will be noted that the passages 84 and 85 are in continuous communication regardless of the vertical position of the ball 79 which is centered in its bore by spring 80 so that there is always a space between the ball and the wall of the bore. Branching from the portion of bore 11 above seat 81 is another passage 88 (Fig. 1) which extends at right-angles to the passages 84-85 and terminates in an enlargement 89 wherein is threaded a pipe fitting 90. The supplemental valve structure described in this paragraph may be considered as being removably attachable to the rest of the organization, since, without in any way interfering with the operation of the main valve, a sub-casing, from which the supplemental valve means are omitted, may be substituted for the one shown.

In Fig. 5, a plurality of the valves described hereinabove, and indicated by the numeral 93, are shown connected to supply fuel to the several main burners 94 and associated pilot burners 95 of a multiple-unit furnace 96, the pilot burners also serving to heat thermoelectric devices (thermocouples or thermopiles) 97, each of which is connected by a cable 98 to the electromagnet 56 of its associated valve. The main burners are connected to the valve outlet connections 14, the pilot burners to the supplemental fittings 90, and the source of gas is connected by a conduit 99, through T-connections, to the main-valve inlet connections 13. Connected in the conduit 99, ahead of the valves 93, is an electrically operated valve 100, a conventional construction, which is automatically controlled by a thermostat 101 responsive to the temperature of a space heated by the furnace. The valve 100 operates normally to turn on and off the supply of fuel to all the main burners 94 as a unit and, for the sake of simplicity, it will be assumed to be continuously open in connection with the following description of the operation of valve 93. For the supply of fuel to the pilot burners 95, a pipe 102 is connected to the conduit 99 at a point ahead of the automatic valve 100 and to the supplemental inlet fitting 86 of the nearest of the valves 93. The other valves 93 are interconnected by pipes 103 extending 75

between their adjacent fittings 87 and 88, so that the supplemental inlet bores or chambers 77 of the several valves are supplied with gas through the passages 84-85 which, as was mentioned hereinabove, are in continuous intercommunication. A plug 104 is substituted for the fitting 87 of the final valve 93.

Operation

10 In Fig. 1 the valve 93 is shown with its parts in the positions which they assume when the cap 35 is manually operated to the limit of its rotation in a clockwise direction, and is held in that position. It will be observed that the plug 16 is in its closed position, so that fuel supply to the main burner 94 is obstructed in spite of the fact that the "safety" closure member 21 is open; and the supplemental valve ball 79 is held away from its seat 81 by the engagement of the depressed arm 26 with the rod 82, so that fuel can now pass from the supplemental inlet chamber or bore 11 through passages 88 and 89 to the pilot burner 95, where it is lighted by a match or other suitable means. The cap 35 is maintained in its manually-held position until the thermoelectric device 97 has become sufficiently heated by the flame of the pilot burner to generate current in an amount sufficient to cause the electromagnet 56 to hold the armature 55 in engagement with the pole faces of its core against the force of the operating-arm spring 34, whereupon the cap may be released. When this occurs, the arm 26 remains in its depressed position (due to its connection with the magnetically-held closure member stem 22) but the rod 29 moves upward under the force of spring 31, the resultant rotation of cap 35 producing no material resistance to the movement of the rod on account of the lost-motion connection between the cap and the plug 16. It will be understood that the angle of rotation of the cap, through which the ball 79 is in engagement with the cam 40, is less than that of the lost-motion between the cap and the tongues 46. Since the supplemental valve ball 79 is now retained in open position by the magnetically-held arm 26 acting through rod 82, fuel still passes to the pilot burner.

45 The plug may now be rotated in a counter-clockwise direction, by means of the cap, to the limit of its rotation wherein the shoulders 49 of plate 43 are in engagement with the stops 47, and the plug passage 18 is in register with the main outlet passage 19 so that fuel passes (through the now-open safety valve) to the main burner 94 where it is ignited by the pilot burner flame. Rotation of the plug back and forth between its open and closed positions is now effective to control fuel supply to the particular main burner to which it is connected, so that any desired number of the individual units of the furnace can selectively be placed under the automatic control of the electrically operated valve 100 to suit particular heating requirements.

50 In the event of extinction of the flame of one of the pilot burners, upon resultant cessation of current generation by the thermoelectric device, the electromagnet to which it is connected releases its armature and the safety closure member 21 moves upward into engagement with its seat under the force of spring 34, so that fuel supply through the open plug valve to the main burner is obstructed. In the resultant upward movement of arm 26, the supplemental valve ball is moved into tight engagement with its seat 81 by

the force of spring 80, thereby shutting off the supply of fuel to the extinguished pilot burner, there being clearance between the rod 82 and the arm 26 when the same is in its raised position. It will be observed that the supplemental valve is operated and held-open effectively solely by the safety closure member and is thus relatively independent of the main operating means.

To reinitiate operation of the burner unit, the valve 83 must be "reset." This is accomplished by rotating the cap through its limit of movement in a clockwise direction (to the position shown in Fig. 1) and holding it in that position while the pilot burner is again lighted, as was described above. It will be observed that, as the cap is rotated, the plug is brought to its fully-closed position before the safety and supplemental valves are opened, the opening of these valves being effected only during approximately the final 10° of rotation of the cap.

While I have herein shown and described a specific embodiment of my invention, I wish it to be understood that modifications may be made without departing from the spirit of the invention, and that I intend therefore to be limited only by the scope of the appended claims.

I claim as my invention:

1. In a fluid control valve: a casing having an inlet and an outlet opening, first valve means movable between an open and a closed position and biased to said closed position for controlling communication between said openings, an arm connected to said first valve means for operating the same, means engageable with said arm for moving the first valve means to its open position, means responsive to a controlling condition for retaining said first valve means in its open position against the force of said bias, a supplemental valve structure having an inlet and an outlet opening, supplemental valve means movable between an open and a closed position and biased to said closed position for controlling communication between said supplemental openings, and means engaged by said arm for moving the supplemental valve means to its open position in the opening movement of said first valve means, the supplemental valve means being retained in open position by said arm regardless of subsequent movement of the means for moving the first valve means.

2. In a fluid control valve: a casing having an inlet and an outlet opening, first valve means movable between an open and a closed position and biased to said closed position for controlling communication between said openings, a pivoted arm connected to said first valve means for operating the same, means movable into and out of engagement with said arm and effective to move the first valve means to its open position, means responsive to a controlling condition for retaining said first valve means in its open position against the force of said bias, a supplemental valve structure having an inlet and an outlet opening, supplemental valve means movable between an open and a closed position and biased to said closed position for controlling commun-

cation between said supplemental openings, and reciprocable means sealingly extending within said casing and engaged by said arm for moving the supplemental valve means to its open position in the opening movement of said first valve means, the supplemental valve means being retained in open position by said arm regardless of movement of the arm-moving means.

3. In a fluid control valve: a casing having an inlet and an outlet opening, first valve means movable between an open and a closed position and biased to said closed position for controlling communication between said openings, an arm for operating said first valve means and connected thereto so as to move therewith, means engageable with said arm for moving the first valve means to its open position, means responsive to a controlling condition for retaining said first valve means in its open position against the force of said bias and said arm in its moved position, a supplemental valve structure having an inlet and an outlet opening, supplemental valve means movable between an open and a closed position and biased to said closed position for controlling communication between said supplemental openings, and means engaged by said arm for moving the supplemental valve means to its open position in the opening movement of said first valve means, said supplemental valve means being retained in open position by said arm regardless of subsequent movement of the arm-moving means.

4. In a fluid control valve: a casing having an inlet and an outlet opening, first valve means reciprocable between an open and a closed position and biased to said closed position for controlling communication between said openings, a pivoted arm pivotally connected to said first valve means for reciprocating the same, means movable into and out of engagement with said arm and effective to move the first valve means to its open position, means responsive to a controlling condition for retaining said first valve means in its open position against the force of said bias and said arm in its moved position, a supplemental valve structure having an inlet and an outlet opening, supplemental valve means movable between an open and a closed position and biased to said closed position for controlling communication between said supplemental openings, and reciprocable means sealingly extending within said casing and engaged by said arm for moving the supplemental valve means to its open position in the opening movement of said first valve means, the supplemental valve means being retained in open position by said arm regardless of subsequent movement of the arm-moving means.

5. A fluid control valve, as set forth in claim 4, wherein the means responsive to a controlling condition comprises an armature connected to said first valve means and an electromagnet for magnetically holding the armature and thereby retaining the first valve means in its open positions.

WILLIAM A. RAY.
